UNITED STATES PATENT OFFICE.

GEORGE WOODHOUSE, OF BUTTE, MONTANA.

VISIBLE INDEX SYSTEM.

Application filed March 31, 1926. Serial No. 98,795.

The present invention appertains to improvements in visible index or accounting systems composed of separate detachable and interchangeable units forming a very compact and economical record arrangement.

In the main it is the object of this invention to provide a novel form of record sheet or card which is designed to be associated with either a temporary holder or folder or a permanent panel frame or cabinet, the construction of the sheet being such that a plurality of the same may be arranged in superposed overlapping relation, each carrying index indicia by means of which ready reference is made possible.

It is further an object to provide means for interlocking the sheets in the holder in such a manner as will permit of their ready removal or interchange for the usual purposes.

Another object of the invention is to provide a filler device for retaining and supporting the interlocked sheets within the frame or support upon which they are mounted.

It is still further an objective to provide a sheet which may itself constitute a holder for ticklers or auxiliary record matter, means also being preferably provided for protecting the edge of the card and coacting with the same to provide a card-receiving pocket.

Other objects and advantages of the invention will be hereinafter set forth and the novel features thereof defined by the appended claims.

In the drawings:

Figure 1 is a perspective view of an index including my special form of index sheet, the carrier therefor, and panel mounting;

Figure 2 is a sectional view on the plane indicated by the line 2—2 of Figure 1; and showing in dotted line the swinging position of the filler element used in conjunction with this device;

Figure 3 is an enlarged fragmentary sectional view showing more clearly the interlocking of the index sheets provided on the reverse side of the same;

Figure 4 is a detail perspective view of a filler member used in conjunction with the holder for maintaining the index sheets positioned in said holder;

Figure 5 is a front elevation of an adaptation of my index in which a transfer or temporary folder is employed for holding the index cards;

Figure 6 shows a rear elevation of the arrangement depicted in Figure 5 with the sheets each broken away at center;

Figure 7 is a detail view of a modified form of index sheet or card together with its carrier partially withdrawn and a removable record card in position;

Figure 8 is a detailed view showing a lower corner of the form of card disclosed in Figure 7 prior to the folding of the same;

Figure 9 is a fragmentary view of a protector piece in unfolded position;

Figure 10 is a fragmentary detail view showing the application of the protector to the index card more clearly;

Figure 11 is a sectional view on the line 11—11 of Figure 10; and

Figure 12 is a plan view of a simplified form of index card or sheet.

Like reference numerals designate corresponding parts throughout the several figures of the drawings.

In the carrying out of this record system or index I employ as one of its novel features a special sheet or card, these terms being interchangeably used, such as disclosed in its simplest form in Figure 12 of the drawings. This sheet comprises the body portion 1 having the flap extension 2 forming a carrier portion, the dividing line 3 between which parts is a score line or line of perforation designed to provide a bendable or flexing connection. The sheet is notched at opposite edges as indicated at 4, 90 preferably in alignment with the score line 3, such notching forming end tabs 5 which in one adaptation of my system at least constitute the means for interlocking the sheet in a specially devised holder. The sheet is 95 arcuately slit at spaced points within the confines of the extension 2 so as to form a pair of ears 6. This slitting is done for two purposes: first to provide openings through which a carrier strip 7 hereinafter referred to may be introduced, and, secondly, to provide a means for spacing one sheet with respect to the other in order to cause the lower edge of an under sheet to project a predetermined amount below 100 the edge of a superposed sheet.

This interlocking arrangement of the sheets is best disclosed in Figure 6 of the drawings wherein it will be observed that the upper edge of each succeeding sheet is 110 engaged beneath the ears 6 of a preceding sheet, resulting in an overlapping disposition

of the respective sheets in the manner best determined by the position of the ears 6 relative to the upper edge of the sheet. When a series of the sheets are interlocked it is desirable to support the same in the holder by retaining means, and various devices may be used for this purpose.

5 of the respective sheets in the manner best determined by the position of the ears 6 relative to the upper edge of the sheet. When a series of the sheets are interlocked it is desirable to support the same in the holder by retaining means, and various devices may be used for this purpose.

10 A further adaptation of this record sheet is shown in Figure 7 of the drawing. The constant handling of the record tends to soil or mutilate the lower edges of the index sheets and for this reason it is desirable to employ some protective means for this edge. I have devised a special form of protector 15 which consists of a sheet of flexible transparent material such as celluloid or the like. Referring to Figure 9, a strip 8 of such material of the proper width is folded longitudinally along the line designated 9 and 20 the opposite edges slit arcuately as indicated at 10 so as to provide an interlocking tongue. In order to mount said protector upon the sheet in a manner which will insure its retention I employ a sheet which is slightly 25 longer than the form illustrated in Figure 12. The lower edge 13 of such a sheet, referring to Figure 8, is folded rearwardly along the line 11 and a notch is then cut in the two plies at opposite edges of the 30 sheet, as indicated at 12. The protector strip is then slipped over the folded edge and the tongue formed by slitting as at 10, is engaged over the lower edge of the notch 12. This protector strip also forms a sup- 35 port for a removable record card 15 as shown in Figure 7, which card may be partially withdrawn at the sides of the sheet 1 for reference purposes, as indicated by dotted lines in said figure. For the purpose of 40 retaining the upper edge of this card in position the sheet is formed with holding ears 16 cut therefrom to engage over the card 15. The sheet 1 and its lower edge 13 bear duplicate index indicia 14 so that when said 45 edge is folded back against the sheet the index is visible even though the sheet be reversed.

45 In Figures 5 and 6 the simplified form of the sheet shown in Figure 12 is illustrated as supported in a holder without the use of the carrier strip, and this may be accomplished by forming the sheet of such width that the tabs 5 will overlap an opening in the holder. In this application of the 55 sheet a holder card or plate 17 is provided with an opening 18 within the body thereof and the tabs 5 overlap the side walls of this opening so as to be slidably mounted therein to permit the interlocking or connection of the sheets by means of the ears 6 formed in the extension 2 thereof, as clearly shown in Figure 6. By this means the sheets are supported in overlapping relation with a portion extended at the lower end for indexing 60 purposes and the extent of this overlap is

5 in the form of the invention shown in Figures 5 and 6 this retaining means comprises a sheet or card 19 which is engaged at its upper edge 20 beneath the ears 6 of the lowermost sheet. The uppermost sheet of the series is retained in the holder against displacement by means of holding ears 21 cut from the support 17 and bent outwards sufficient for the purpose while the lower portion of the retaining card 19 is supported by similar ears 22, disposed adjacent the lower edge of the opening 18 in the holder. This card 19 is of material suitable to be flexed into position and thus support the assembled sheets at the upper portion in the opening of the holder.

10 In the form of the invention shown in Figures 5 and 6 this retaining means comprises a sheet or card 19 which is engaged at its upper edge 20 beneath the ears 6 of the lowermost sheet. The uppermost sheet of the series is retained in the holder against displacement by means of holding ears 21 cut from the support 17 and bent outwards sufficient for the purpose while the lower portion of the retaining card 19 is supported by similar ears 22, disposed adjacent the lower edge of the opening 18 in the holder. This card 19 is of material suitable to be flexed into position and thus support the assembled sheets at the upper portion in the opening of the holder.

15 A convenient form for mounting this holder may comprise a folder 23 as shown in Figure 5, to which the holder is affixed by any desired means such as the staples 24, and the upper leaf of the cover folds over and encloses the sheets to protect the same in their assembled relation. The mounting of the sheets in this form of holder is 20 facilitated by the notch 4 at each side thereof which disposes the tab 5 at the rear of the holder and the body of the sheet in contact with the front face thereof.

25 In Figures 1 to 3 the sheets such as shown in Figure 7 are adapted to be mounted in a frame type of holder 25, the edges of which are channeled. The channels 26 at the side edges of the holder receive the projecting ends of the carrier strip 7 before described, which are mounted in the extensions 2 of the card by means of the slits that define the outer edges of the ears 6 thereon. These ears also overlap and interlock with the extension 2 at the upper edge of the next 30 adjacent sheet as described in connection with Figures 5 and 6 so as to assemble the sheets in a series overlapping and spaced from each other at their lower edges. The extension 2 of the upper sheet is disposed within the channel 26 of the frame or holder and is held in such position by means of a retainer 27 comprising a plate engaging the ends of the strip 7 of the lowermost sheet within the channels 26 into which the edges 35 of the retainer extend as shown in Figure 3. This plate is mounted upon a yielding holder 28 which is pivotally connected by the clip 29 with the retainer 27.

40 The opposite ends of the spring 28 comprising this holder are seated against rotative movement in the groove 30 at the lower edge of the frame and the retainer is thus held in contact with the cards under a yielding tension which permits a downward slid- 45

ing and outward swinging movement thereof if it be desired to remove or replace any of the sheets of the series.

The edges 31 of the retainer extend into the channels 26 of the frame and the upper edge thereof may be cut away at 32 to form a fingerhold for the purpose of flexing the retainer laterally, as indicated by dotted lines in Fig. 4, if it be desired to remove the latter from the frame. When so flexed the holder may be swung outward away from the sheets as indicated by dotted lines in Figure 2. When it is desired to swing the retainer 27 outwardly to release the sheets 15 they are lifted to a substantially horizontal position permitting access to the retainer which is at other times practically in contact with the rear of the holder 25.

The operation of the invention will be apparent from the foregoing description from which it will be seen that the form of sheet used comprises a unit member adapted to be inserted in a typewriting machine for the application of any desired data or indexing 25 thereon, and subsequently assembled with similar sheets by means of the interlocking connection so disposed that the series of sheets are spaced from each other at their lower ends rendering a portion visible for 30 index indicia and convenient handling of the sheet when access is desired thereto. While the sheets may be so interlocked to form a visible index, they may be suitably supported upon any desired type of holder, 35 but the use of the retainer is found of importance as it retains the sheets in their proper spaced relations in the holder and prevents unauthorized removal of any of the sheets by an outward tension thereon. The 40 sheets being interlocked cannot be directly withdrawn but must be separated from each other before their removal. The protector provided at the lower end of the sheet forms a desirable fingerhold for grasping the sheet 45 and protects the index indicia thereon while forming means by which the removable record card may be supported upon the face of the sheet in connection with the holding ears provided for that purpose. This protector 50 is readily removable and may be applied as desired.

While the specific construction of the sheets and means for mounting the same has been shown and described, the invention is 55 not confined thereto as changes and alterations may be made without departing from the spirit of the invention as defined by the appended claims.

Having thus described my invention, what 60 I claim as new and desire to secure by Letters Patent is:

1. In an index, the combination with a holder, of a plurality of sheet carriers slidably mounted therein in parallel relation, 65 sheets supported by said carriers and hav-

ing projections from the face thereof adapted to engage an edge of a parallel sheet and space the sheets in parallel overlapping relation, and a filler device coacting with the carrier upon the lowermost sheet to maintain the carriers positioned adjacent each other.

2. In an index, the combination with a holder, of a plurality of sheet carriers, sheets having flaps cut from the body thereof to provide apertures to receive the carriers to support the sheets, said flaps constituting stops for an adjacent sheet by engaging its upper edge to cause the edges of the sheets to overlap.

3. In an index, the combination with a holder, of a plurality of sheet carriers slidably mounted at their side edges therein, sheets each supported by one of said carriers and having an extension bendably connected with the upper portion thereof, and interlocking means formed from said extension and adapted to overlap the extension of an adjacent sheet.

4. An index card or sheet comprising a body portion having a bendably connected extension, and a removable carrier member mounted in said extension and projecting beyond the side edges thereof, said carrier being retained by passage through apertures in said extension.

5. An index card or sheet comprising a body portion provided at its upper end with means for supporting the same in a holder and at its lower end with a rebent portion, 100 means for attaching said rebent portion to the body of the card at each side thereof to form retaining means for a record card, and holding projections from said body disposed to embrace the upper edge of said card.

6. An index card or sheet comprising a body portion provided with means for supporting the same in a holder and recesses at the lower side edges thereof, and a protector bent upon itself to embrace said edges and formed with a tongue cut therefrom so as to project from its base toward the bend line to interlock with said recesses.

7. In a card index, the combination with a holder, of a series of associated sheets slidably mounted therein and adapted to engage the upper portion of the holder, and a retaining device supported by the lower portion of the holder and adapted to be withdrawn laterally of the assembled sheets.

8. In a card index, the combination with a holder, of a series of associated sheets slidably mounted therein and adapted to engage the upper portion of the holder, a retaining device comprising a card adapted to engage the lowermost sheet and the holder, and a supporting spring for said card pivotally connected thereto.

In testimony whereof I affix my signature.
GEORGE WOODHOUSE.
